UNITED STATES PATENT OFFICE.

ROBERT C. MYERS, OF HUTCHINSON, KANSAS.

SPARK PLUG.

Application filed March 23, 1925. Serial No. 17,751.

This invention relates to improvements in spark plugs.

The primary object of this invention is the provision of a novel type of spark plug embodying an electrode adapted to be cooperatively associated with the piston of an internal combustion engine for the production of the necessary spark; the piston being adapted to engage the spark plug electrode at its upward movement, to slightly flex the same and engage it for the purpose of cleaning the same and rendering the same effective for subsequently producing a spark.

15 A further object of this invention is the provision of a novel type of spark plug which is particularly well adapted to be used in connection with various types of internal combustion engines; embodying novel 20 electrode and electrode adjusting means to properly position the spark plug electrode in sparking relation to the movable piston of the cylinder with which it is associated.

A further object of this invention is the 25 provision of a novel type of spark plug embodying an arrangement which particularly well adapts the same to be assembled in a novel manner, and including an insulated central electrode which may be held 30 in a positive relation with respect to the spark plug shell after the latter has been placed in the engine block.

Other objects and advantages of this invention will be apparent during the course 35 of the following detailed description.

In the accompanying drawing, forming 40 a part of this specification, and wherein similar reference characters designate corresponding parts throughout the several views,

Figure 1 is a fragmentary sectional view taken through the top portion of an internal combustion engine cylinder block showing the improved spark plug and its electrode 45 cooperating relation with the piston of the engine.

Figure 2 is an enlarged vertical sectional view taken through the improved spark plug.

50 Figure 3 is a cross sectional view taken through the improved spark plug substantially on the line 3-3 of Figure 2.

Figure 4 is a side elevation of a novel 55 type of insulating core for the spark plug, and the novel central electrode carried thereby.

Figure 5 is a plan view of the improved spark plug.

In the drawing, wherein for the purpose of illustration is shown only a preferred embodiment of this invention, the letter A may generally designate an internal combustion engine of any approved type, which may comprise an engine housing or block B, within which a piston C is slidably disposed. 65 The novel spark plug D is adapted to be detachably carried by the housing or cylinder block B in a novel cooperating relation with respect to the piston C.

With the type of internal combustion engine A a cylinder chamber 10^a is provided therein, and this type of engine A which is probably the most common, is provided with an internally screw threaded spark plug opening 11 thru the top wall 12 thereof; 70 the axis of the opening 11 preferably being laterally offset with respect to the chamber 10^a within which the piston C operates. Such a construction is of a form most difficult to provide with a spark plug having 75 an electrode which is adapted to be engaged by the piston C upon its compression stroke.

Referring to the spark plug D, the same is a departure from conventional spark plug constructions, in that only a single electrode 80 is carried thereby, which is insulated from the shell portion thereof, and which electrode really cooperates with the piston C; the latter in this case providing the other electrode necessary to produce the spark. 85 To this end the spark plug D comprises the metal shell 10; insulating core 11; electrode 12; washer 14 adapted to be positioned on the shell 10 for receiving the core 11 thereon; metal clamping nut or cap 15; and washer 16 for sealing the juncture at the point of engagement of the clamping cap or nut 15 on the core 11.

The metal shell 10 preferably comprises 100 the hollow body portion 18, providing an external polygonal wrench engaging surface. Below the body 18 an inwardly extending annular flange 19 is provided integral with the body 18, for the purpose of providing the upwardly facing annular shoulder 20 adapted to receive the washer 14 thereon, and for supporting the core 11, as in well known construction. Integrally depending from the inner edge of the flange 19 is the externally screw threaded hollow 105 cylinder inserting shank 22, which is of a diameter to permit its detachable insertion 110

in the screw threaded opening 11 of the internal combustion engine housing B. The shank 22 provides the passageway 24 therethrough, downwardly through which the 5 electrode 12 may project, as is illustrated in the drawing. Integral with the body 18, and radially extending inwardly of the compartment 26 thereof is a lug 27, spaced just above the shoulder surface 20, and which is provided for the dual purpose of retaining the 10 washer 14 placed, and for the major purpose of preventing the core 11 from rotation with respect to the metal shell 10, as will be subsequently described.

15 The washers 14 and 16 are of copper covered asbestos type, and they are of preferably the same diameter, adapted to be slipped into the compartment 26 of the shell body 18; the lower washer 14 being adapted 20 to rest upon the shoulder surface 20 below the lug 27, which as before mentioned is spaced upwardly above the shoulder surface to permit the washer to so seat.

25 The core 11 is preferably made of blue porcelain, or any other preferred insulating material, and it comprises the substantially cylindrical shaped body portion 30, upwardly from which and downwardly from which the reduced shanks 31 and 32 respectively 30 extend. At the juncture of the body 30 and upper tapered hexagonal shank 31 a shoulder 33 is provided, upon which the washer 16 is adapted to seat to enable a clamping action of the nut or cap 15 thereagainst. In 35 similar manner at the juncture of the lowermost reduced shank 32 and the body 30, a downwardly sloping converging shoulder 35 is provided, adapted to rest upon the washer 14, just upwardly of the shoulder 20. 40 The core 11 axially therethrough is provided with the electrode receiving passageway 37, which at the lower end thereof is enlarged, as at 38, opening at the lower edge 39 of the reduced shank 32. A novel feature 45 of the core construction 11 is the provision of slots or recesses 40 inwardly of the outer periphery of the body 30, communicating downwardly through the shoulder 35, and which are provided in any approved number 50 about the body 30, although preferably six of the same are provided. These recesses are adapted to receive the metal shell lug 27, for the purpose of maintaining the core 11 in a fixed relation with respect to the shell 10, 55 in order to properly position the electrode 12 in a definite relation.

60 Referring to the electrode 12, the same is of any approved type of metal, comprising the vertical straight body portion 50, adapted to be received in the core passageway 37. Between its ends this portion 50 is provided with an annular rigid flange or abutment portion 51, which is adapted to be slipped upwardly into the enlarged portion 38 of the 65 recess 37, for abutment against the down-

wardly facing shoulder at the juncture of the enlarged portion 38 with the reduced portions of the passageway 37, for the purpose of limiting the upward movement of the body portion 50 in the core 11. At its 70 upper end the electrode 12 is screw threaded, as at 55, for detachably receiving a conventional type of terminal clamping nut and washer construction 56. The electrode 12 at its lower end is of somewhat 75 novel construction. When it is assembled in the shell 10, the lower end portion of the straight body 50 of said electrode extends for a short distance below the bottom edge 58 of the shell 10. From this point 80 the electrode has an integral downwardly sloping relatively long portion 60, which is of a length preferably greater than the internal diameter of the passageway 24 of the shell 10, and disposed in an obtuse angular relation with respect to the axis of the body portion 50 of the electrode. At the free end of the downwardly sloping portion 60, a downwardly projecting spark shank 61 is provided, arranged at an axis 85 parallel with that of the body portion 50, and of course extending in an opposite direction from the body portion 50; the lower edge 62 thereof preferably being flat and in a plane at right angles to the axis of the 90 shank 61.

95 Referring to the use of the improved spark plug, the metal shell 10 is first placed in the engine housing B, by screwing the same to a set position in the screw threaded opening 11. The washer or gasket 14 is then placed in the position above described, if the same has not already been placed, and the porcelain core 11 is then inserted into the shell 10. Of course, the electrode 12 has 100 already been assembled in the core 11, so that upon tipping of the core 11 the lower end portion of the electrode 12 may be passed through the shell. The core 11 is now circumferentially adjusted until the sparking 105 shank 61 at the free end of the electrode 12 is disposed immediately over the piston C, where the latter can engage the edge 62 upon upward movement at the compression stroke. In this position the core 11 is locked to the 110 shell 10 by the lug 27 being received in one of the recesses 40. The upper washer 16 is then placed on the shoulder 33, and the clamping nut 15 adjusted to a set position 115 in accordance with conventional construction.

120 From the foregoing description of this invention it is apparent that a novel type of spark plug has been provided, which embodies novel features in that the same permits an assemblage of parts which will enable the spark plug to be used with all types of internal combustion engines, so that an electrode thereof may cooperate in an engaging manner with the piston of the engine. 125 130

The fact that the core and electrode is maintained in a positive adjustment with respect to the shell of the spark plug and the engine housing insures that an adjustment thus made will be maintained indefinitely.

Various changes in the shape, size, and arrangement of parts may be made to the form of invention herein shown and described, without departing from the spirit 10 of this invention or the scope of the claims.

I claim:

1. In combination with an internal combustion engine including a casing provided with a cylinder chamber and a spark plug 15 inserting opening in the casing above and axially offset from the cylinder chamber, a spark plug for said spark plug inserting opening, said spark plug including an insulating core and an electrode carried by said 20 insulating core, said electrode at its inner end providing a relatively long flexible offset extending into the cylinder chamber for engagement by the piston upon topmost movement of the latter.

2. As an article of manufacture a spark plug electrode comprising a straight main body portion, an offset at an end of said straight body portion disposed in obtuse angular relation with said body portion and beyond the outer confines of the body portion, and a straight sparking shank at the outer end of said offset extending in opposite direction from the body portion and disposed with its axis in parallel relation with 30 said body portion.

3. A spark plug comprising a shell, an insulating core, means mounting the insulating core in said shell, and an electrode carried by said core extending below the shell 40 and providing a relatively long lateral offset disposed with its axis in oblique angular relation to the axis of said spark plug, said offset at its free end being disposed laterally of the exterior of the shell and there- 45 at providing a downwardly extending spark-

ing shank substantially parallel with the axis of the spark plug.

4. In combination with an internal combustion engine including a casing having a 50 cylinder chamber and a piston slidable therein, and being provided with a spark plug opening, a spark plug for detachable mounting in the spark plug opening including a flexible electrode laterally extending 55 into the cylinder chamber beyond an end of the piston and adapted to be engaged by the piston at the end of its stroke to cause the flexing of the electrode.

5. In combination with an internal combustion engine including a casing provided with a cylinder chamber and a spark plug inserting opening beyond an end of the piston, and a spark plug for the spark plug opening including an end for inserting into 60 the opening and an electrode extending from the end and laterally extending into the cylinder chamber beyond an end of the piston transversely arranged with respect to the axis of the piston and of a length sufficient 65 to permit the same to be engaged by the piston at the end of a stroke to flex to said electrode slightly.

6. In combination with an internal combustion engine including a casing having a 75 cylinder chamber, a piston slidable in the cylinder chamber, the cylinder chamber above the piston having a spark plug inserting opening communicating therewith, the spark plug inserting opening being disposed in 80 parallel axial relation with the cylinder chamber and laterally offset from the piston, and a spark plug detachably mounted in said spark plug inserting opening having a relatively long laterally extending electrode 85 portion projecting into the chamber above the piston and laterally extending towards the piston into relation to be engaged by the top of the piston at its top stroke, the said portion of the electrode being flexible.
